UNITED STATES PATENT OFFICE.

HERBERT JERSTRUM, OF CHICAGO, ILLINOIS, ASSIGNOR TO HERBERT A. STREETER, OF SAME PLACE.

CIGAR-BUNCH MACHINE.

SPECIFICATION forming part of Letters Patent No. 673,124, dated April 30, 1901.

Application filed March 26, 1898. Serial No. 676,333. (No model.)

To all whom it may concern:

Be it known that I, HERBERT JERSTRUM, a citizen of the United States, residing in Chicago, in the county of Cook and State of Illinois, have invented a new and useful Improvement in Cigar-Bunch Machines, of which the following is a specification.

My invention relates to improvements in cigar-bunch machines, and more particularly to improvements on the cigar-bunch machines heretofore patented to me in Letters Patent of the United States No. 528,166, of October 30, 1894; No. 536,630, of April 2, 1895, and No. 588,912, of August 24, 1897.

The objects of my invention are to improve and simplify the construction and operation of the machine of my said patents, to facilitate the feeding of the tobacco to the bunch forming and compressing devices, and to secure uniformity in the bunches produced by the machine.

My improvement consists in the combination, with a compressing-plunger, a charger, a movable sectional bottom for the charger, and the knives or cutters for severing the charge, of an endless flexible feeder operating to feed or convey the tobacco in a continuous stream about the width of the bunch or charger into position to be operated upon by the compressing-plunger, charger, movable sectional bottom, and knives, and comprising, essentially, a pair of endless flexible belts traveling on a pair of horizontal pulleys and provided each with a series of blocks forming the side walls of the feeder, the two belts being placed a short distance apart to give room for the tobacco between the blocks. The upper and lower loops of the endless flexible feeder pass over bed-plates, which

support the tobacco or keep it in position in the endless groove or channel between the two series of blocks on the two endless belts. The lower bed-plate or tobacco-supporting part is provided with an opening for the movable sectional bottom to work up and down through, and the compressing-plunger works up and down between the upper and lower loops or portions of the endless flexible feeder, and to keep the tobacco in position at the curved portion of the endless flexible feeder, where the same passes around the pulleys, curved shoes are provided.

My invention also consists in the novel construction of parts and devices and in the novel combinations of parts and devices herein shown and described, and specified in the claims.

In the accompanying drawings, forming a part of this specification, Figure 1 is a plan view of a machine embodying my invention. Fig. 2 is a side elevation. Fig. 3 is a front elevation. Fig. 4 is a longitudinal section on the line 4-4 of Fig. 1. Fig. 5 is an enlarged cross-section of the flexible feeder on the line 5-5 of Fig. 4. Fig. 6 is an enlarged cross-section on the line 6-6 of Fig. 4. Fig. 7 is a detail longitudinal section on the line 4-4 of Fig. 1. Fig. 8 is a sectional view similar to Fig. 7, showing the parts in a different position. Fig. 9 is a detail section on the line 9-9 of Fig. 6. Figs. 10, 11, and 12 are detail views, partly in section, showing the bunch-rolling mechanism.

In the drawings similar letters of reference indicate like parts throughout all the figures.

In said drawings, A represents the frame of the machine.

B is the endless flexible feeder, the same having a continuous endless channel B' to receive the tobacco in a continuous endless stream and convey it to the charger, compressing-plunger, and other co-operating parts. This endless flexible feeder is preferably composed of two parallel belts b b, each provided with a series of short blocks b', secured thereto to form the sides or walls of the tobacco-channel B'. The two belts or bands b b are placed just far enough apart to form the tobacco-channel B' and which should correspond in width to the charger C.

B² B² are horizontal pulleys upon which the endless flexible feeder travels.

B³ is a tobacco-supporting plate or bed-plate, over which the upper loop or parallel portion of the endless flexible feeder B travels, and B⁴ is a similar bed or supporting plate for the lower loop or portion of the endless flexible feeder to travel over. This lower plate B⁴ is provided with an opening B⁵ for the movable sectional bottom D to work up and down through and the guide-grooves B⁶ for the two parallel belts b b. The upper supporting plate or bar B⁸ is likewise provided with guide-grooves B⁷ B⁷ for the belts b b. Curved shoes B⁸ B⁹, extending each half

around the pulleys B^2 or B^2 , serve to keep the tobacco in position between the two series of blocks b' on the two belts b of the endless flexible feeder, and thus to cause the tobacco 5 to be carried around the pulleys B^2 B^2 in a continuous path. As the channel B' for the tobacco is thus a continuous and endless one the surplus tobacco severed or sheared from the charger by the knives at each operation 10 is or may be thus continuously kept in the feeder and redelivered into position for forming a charge. In other words, the operator places the tobacco in the upper course of the feeder, and it is carried thence under shoe B^8 15 and over pulley B^2 at the left of Fig. 4. It then passes along table B^4 to the charger, where the surplus, if any, is severed from the charge and left in the feeder-channel. This surplus is carried by the feeder around pulley B^2 at the right of Fig. 4 and along the upper course of the channel to the starting-point, where the fresh tobacco is being added. While the tobacco is moving over plate B^4 , 20 more tobacco may be added, if necessary, as 25 full access to the feeder-channel is permitted while it is moving between the left pulley B^2 and the charger.

The charger C has a horizontally-swinging movement to carry it from the charge-receiving position, where it registers and co-operates 30 with the endless flexible feeder B , the movable sectional bottom D , and the compressing-plunger E , to the position where it registers and co-operates with the discharging-plunger 35 F and the rolling-table G and apron H . In order to give the charger this horizontal swinging movement, it is secured to a horizontal vibrating swinging arm C' , secured to a vertical shaft C^2 , which is operated by a 40 pinion C^3 thereon, that engages a vibrating segment-gear C^4 .

The movable sectional bottom D is composed of a series of separate sections d , mounted to reciprocate independently of each other 45 in a vertical reciprocating slide or cross-head D' , by which the sectional bottom as a whole is moved up and down to force a charge of tobacco from the tobacco in the feeder-channel B' up into the charger C and above the 50 reciprocating knives K K' , by which the charge in the charger is severed from the main tobacco-supply in the channel B' of the feeder. Each of the movable sections d is provided with a stem d' , having a collar d^2 loose thereon and a spring d^3 . The slide D' is moved 55 up and down by a cam m on the cam-shaft M . The tension on each of the springs d^3 is varied and regulated to force more tobacco into the charger at the central portion, so as to give 60 the required cigar shape to the charge by a series of independently-adjustable levers D^2 —one for each section d —which are pivoted at D^3 to the frame and engage at their outer ends adjusting-screws D^4 , which are mounted 65 upon a vertically-reciprocating slide D^5 , that is given the same, but a reverse, up-and-down movement as the slide D' by means of a cam

m' , similar to the cam m on the cam-shaft M . The long arms of the levers D^2 fit under the collars d^2 on the stems d' , so that any adjustment of any lever D^2 by the screw D^4 bearing against the short arm increases the action of the long arm against the spring d^3 . 70

The compressing-plunger E has a curved or bellied under face E' and is secured to reciprocating stems E^2 E^2 and moves up and down in a bracket E^3 , attached to the frame. The stems E^2 E^2 are adjustably secured by screws E^4 to a connecting-bar E^5 . The compressing-plunger E is operated by a lever E^6 , adjustably connected by a threaded bolt E^7 to the connecting-bar E^5 , said lever E^6 being operated by a cam m^2 on the cam-shaft M through a connecting-lever E^8 and link E^9 . 75 80

The knives K K' are caused to reciprocate 85 between the lower face of the charger C and the upper face of the endless flexible feeder B , and thus to sever the filled charge in the charger from the main supply of tobacco in the feeder-channel B' when the movable sectional bottom D has forced the filler charge into the charger. This will be readily understood by reference to Figs. 6 and 8. When the charger C swings horizontally to convey the charge from the charge-receiving station to the 90 charge-discharging station, the closed knives K K' , in connection with the upper surface of the table A' , serve to support the charge in the charger. The knife K is reciprocated horizontally by means of a reciprocating slide or carriage K^2 , to which said knife is secured and which is moved back and forth as required by means of a cam m^4 on the cam-shaft M engaging rollers K^3 on said carriage K^2 . The other knife K' is reciprocated as required 100 by a slide K^4 , which is operated by a lever K^5 105 engaging a cam m^5 on the cam-shaft M .

The discharging-plunger F is adjustably secured by a set-screw f to a reciprocating cross-head F' , mounted in suitable guides F^2 on the frame of the machine, and is moved up and down as required by a cam m^6 on the cam-shaft M through the connecting-lever F^3 and link F^4 . 110

The rolling-table G is preferably of a curved 115 form, as indicated in the drawings, and is provided with a cavity g to give room for the bunching-roller O and the sag or slack h of the apron H , as will be clearly understood from Fig. 10. The rolling-table G is attached 120 to or made integral with a movable lever G' , by which the table is moved up and down to bring it into position to receive the charge, as illustrated in Fig. 10, and then in position to permit the bunching-roller O and apron H to 125 roll the binder around the charge, as illustrated in Figs. 11 and 12. The rolling-table carrying lever G' is thus operated by a cam m^6 on the cam-shaft M . The bunching-roller O is swung or moved over the curved surface 130 of the table G as required to cause the apron H to roll the binder about the filler charge by means of a cam m^7 on the cam-shaft M engaging a lever O' , connected by a link O^2 and 135

spring O³ with the bent lever O⁴, upon which the roller O is mounted.

To facilitate the passage of the continuous stream of tobacco in the feeder-channel B' under the charger C, I provide a feed-roller B¹⁰ above the feeder-channel, and also a curved shoe B¹¹, both of these parts being mounted on the stationary frame of the machine.

The endless flexible feeder B is intermittently driven by a lever T, having a roller t engaging the cam m on the shaft M, which is connected by a rod T' with a lever T², pivoted on the shaft of one of the pulleys B² and which is furnished with a pawl T³, that engages a ratchet T⁴ on said pulley. The lever T is furnished with a slot t', so that its operative length may be adjusted as required to adapt the feed or forward movement of the feeder B to different lengths of cigar-bunch.

20 I claim—

1. In a cigar-bunching machine, the combination with upper and lower bed or supporting plates, of an endless flexible feeder comprising a pair of parallel belts each furnished with a series of sectional blocks and moving side by side throughout their travel, to form an endless, flexible channel between the two series of blocks, a horizontally-movable charger, a compressing-plunger, a movable sectional bottom adapted to be moved up between said block-armed belts, a pair of horizontally-reciprocating knives, a discharging-plunger, and a rolling-table, apron and bunching-roller, substantially as specified.

35 2. In a cigar-bunching machine, the combination with upper and lower bed or tobacco-supporting plates, of an endless flexible feeder, comprising a pair of belts traveling on horizontal pulleys and side by side throughout their travel, and each furnished with a series of short blocks to form the side walls of the continuous tobacco-channel, substantially as specified.

45 3. In a cigar-bunching machine, the combination with a compressing-plunger, a charger, and a movable bottom, of an endless flexible feeder comprising a pair of belts armed with short blocks and moving side by side throughout their travel, and horizontal pulleys upon which the belts travel, substantially as specified.

55 4. In a bunching-machine, the combination with a pair of pulleys rotating on horizontal axes, of a pair of endless flexible belts traveling on said pulleys side by side throughout their travel and armed with short sections forming the side walls of the traveling tobacco-feed channel, substantially as specified.

60 5. The combination with a pair of pulleys rotating on horizontal axes, of a pair of tobacco-feed belts moving side by side throughout their travel and armed with short sections to form the side walls of the tobacco-feed channel, and upper and lower bed-plates 65 furnished with guides for said belts, substantially as specified.

6. The combination with a pair of horizontal pulleys, of a pair of tobacco-feed belts moving side by side throughout their travel and armed with short sections to form the 70 side walls of the tobacco-feed channel, upper and lower bed-plates furnished with guides for said belts, and curved shoes extending around the outer half of said pulleys, substantially as specified.

75 7. In a bunching-machine, the combination of a continuous endless flexible feeder, comprising a pair of flexible belts moving side by side throughout their travel and armed with short sections, a charger above said belts, a compressing-plunger, a movable bottom below said belts, and a feed-roller co-operating with the endless flexible feeder, substantially as specified.

80 8. In a cigar-bunching machine, the combination with the charger and compressing-plunger, of a movable sectional bottom, comprising a series of sections d, mounted on a reciprocating slide D' and provided each with a stem d', spring d³ and loose collar d², and 90 a series of adjusting-levers D² one for each section fitting at one end under said collars and bearing at the other end against a series of adjusting-screws mounted on a second reciprocating slide, and means for operating 95 said slides in opposite directions, substantially as specified.

9. The combination with an endless, flexible, tobacco-feeder consisting of two parallel belts arranged and moving side by side as 100 set forth, of a horizontally-swinging charger above said belts, a compressing-plunger and a movable bottom below said belts, substantially as specified.

10. The combination with an endless, flexible, tobacco-feeder consisting of two parallel belts arranged and moving side by side as 105 set forth, of a horizontally-swinging charger above said belts, a compressing-plunger and a movable sectional bottom below said belts, 110 substantially as specified.

11. The combination with an endless, flexible, tobacco-feeder consisting of two parallel belts arranged and moving side by side as 115 set forth, of a horizontally-swinging charger above said belts, a compressing-plunger, a movable bottom below said belts, a discharging-plunger, a rolling-table, apron and bunching-roller, substantially as specified.

12. In a bunching-machine, the combination 120 with a continuous endless, flexible feeder, consisting of two parallel belts arranged and moving side by side as set forth, and having a continuous tobacco-holding channel between said belts, of pulleys rotating on horizontal axes for said belts, and curved shoes, 125 substantially as specified.

HERBERT JERSTRUM.
